UNITED STATES PATENT OFFICE.

WILLIAM LONSDALE, OF ROSELLE PARK, NEW JERSEY, ASSIGNOR TO WHEELER CONDENSER & ENGINEERING COMPANY, OF CARTERET, NEW JERSEY.

CONDENSER.

Application filed October 3, 1922. Serial No. 592,176.

To all whom it may concern:

Be it known that I, WILLIAM LONSDALE, a citizen of the United States, residing at Roselle Park, in the county of Union and State of New Jersey, have invented certain new and useful Improvements in Condensers, of which the following is a specification.

This invention relates to surface condensers for steam engines, turbines and the like.

In large condensers it is difficult to distribute the exhaust steam uniformly to all parts of the cooling surface, and difficult to cool the non-condensable gases (air) sufficiently to secure efficient operation of the air pump unless the condensate be unduly cooled, i. e. cooled to a temperature materially below that corresponding to the effective absolute pressure in the condenser.

In a prior application, Serial No. 592,174, filed October 3, 1922, I describe and claim an apparatus for condensing steam which avoids the above difficulties. The cooling surface is subdivided into small units and air and condensate are separately withdrawn by means closely associated with each unit. In a typical structure the water tubes are arranged in clusters, to form a plurality of cooling units, each of which has at its center an air offtake leading to a vacuum chamber or manifold from which the air pump draws. Each cluster also has beneath it a condensate collecting tray which catches condensate flowing from the tubes and leads it directly to the hot well without further contact with water tubes. The vacuum chamber is readily arranged to be traversed by the water tubes and thus serves as an air cooler. Each tube cluster is dimensioned to produce complete condensation without over-cooling and the condensate is protected from subsequent cooling action by the collecting trays which keep it out of contact with the tubes. The air is withdrawn at many points throughout the condenser, thus preventing the formation of air pockets, and tending to distribute the steam flow in the condenser so as to balance the load on the various clusters. Furthermore the air is cooled in the condenser, but only after it has been separated and isolated from the condensate.

The broad inventive concept above out-

lined is claimed in the application above identified together with the preferred specific embodiment, and hence is not claimed herein. In the prior application, however, the suggestion is made that the broad features of the invention may be embodied in a structure in which no internal cooler for the non-condensable gases is included in the condenser structure, the condenser so modified being intended for use with well known types of external cooler.

The present application is designed to disclose and claim specifically a condenser structure embodying the essential features of the invention broadly claimed in the prior application, but designed for use with an external cooler for the non-condensable gases. As incidental features the structure upon which the present application is based includes a special arrangement of the water tubes and vacuum tubes, insuring very short flow paths for exhaust steam and condensate within the condenser and providing an extremely simple construction by which the highest thermal efficiency may be secured.

Stated in its simplest terms, the present structure embodies a water tube condenser having its water tubes arranged in two main groups with an intervening steam and condensate lane leading from the exhaust steam inlet at the top of the condenser shell to the hot well at the bottom of the shell, the tubes of the two groups being subdivided by deflectors which serve to discharge the condensate from each group into the central lane. This subdivision of the water tubes permits easy access of the steam to the various subgroups and at the same time insures that the condensate from each subgroup will be discharged through the lane to the hot well and not over the tubes of the lower groups. An arrangement of this sort is useful even with conventional types of air pump connection, but far better action is secured by associating with each subgroup one or more off-takes for non-condensable gases, such off-takes being positioned at points remote from the steam lane so that the outflow of non-condensable gases serves in part to induce a proportional flow of exhaust steam to the various subgroups of water tubes.

The preferred embodiment of the inven-

tion is illustrated in the accompanying drawings, in which:-

Fig. 1 is a side view of the condenser, partly in elevation and partly in section, on the line 1-1 of Fig. 2.

Fig. 2 is a vertical transverse section on the line 2-2 of Fig. 1, some of the water tubes being omitted.

The shell of the condenser is shown at 6, 10 the exhaust steam connection at 7, the hot well at 8, the water boxes at 9 and 10 and the water connections at 11 and 12. The water box 10 is subdivided by a horizontal partition 13, providing a two-pass arrangement for the cooling water, as is well understood. The tube sheets are shown at 14 and 15, and the water tubes at 16. These tubes are mounted in the tube sheets in the usual manner, but, as best shown in Fig. 2, are 20 arranged in two main groups, separated by a central substantially vertical steam lane 17, which provides a direct flow path from the exhaust steam inlet connection 7 through the body of the condenser.

25 The two main groups of tubes 16 are further subdivided into subgroups by means of the slightly inclined deflectors consisting of plates 18, which are supported on the shell of the condenser by angle brackets 19 and 30 which extend inward to the steam lane 17 so as to discharge condensate well within the steam lane out of contact with water tubes 16. These plates offer the simplest condensate deflecting means known to me, 35 but other substantially equivalent arrangements will suggest themselves and may be adopted if preferred. Besides deflecting the condensate these plates serve to divide the cooling surface into a plurality of subgroups or clusters, each of which may be, 40 and preferably is, proportioned to produce complete condensation of a proportional amount of the total exhaust steam, without undue cooling of the resulting condensate.

45 The structure so far described is of particular utility because a free path to each subdivision of the cooling surface is afforded to the exhaust steam, and at the same time the condensate is discharged to the hot 50 well through this same steam lane out of contact with the cooling surface. To secure the best effect, however, I provide a special arrangement for the dry air or vacuum pump by which this pump is caused to draw 55 non-condensable gases from points closely associated with each subgroup of water tubes.

In the best embodiment of this idea known 60 to me, these offtakes are arranged to draw non-condensable gases from points remote 65 from the steam lane 17 and preferably adjacent to the shell of the condenser, and the offtakes are arranged to extend the entire length of the water tubes and are provided 70 with inlets at points throughout their entire

length. This avoids the formation of air pockets in the condenser, induces an even flow of exhaust steam and non-condensable gases through the various subdivisions of the cooling surface and generally tends to 70 an equalization of the load on all parts of the condenser.

In the preferred embodiment, these off-takes consist of perforated tubes 20 which extend between the tube sheets 14 and 15, 75 and which are supported therein. The ends of the tubes 20 are, however, plugged, as indicated at 21, so that no water may enter the tubes from the water boxes. Each tube 20 is provided with a connection 22 leading 80 through the shell 6 of the condenser and thence to a manifold structure 23. Two such manifold structures are shown in Fig. 2, and it is contemplated that these two manifolds will be connected to a cooling 85 structure external to the condenser and thence to the usual dry air pump. As the use of such external coolers is familiar to those skilled in the art, it is not necessary to illustrate this feature of the installation. 90

While I show one offtake or vacuum tube 20 associated with each subgroup of the cooling tubes, it is obvious that more might be used in the event, for example, that the subgroups were so large that it became desirable to withdraw the non-condensable gases at more points within the subgroup. It should be observed that each vacuum tube 20, by reason of the provision of a plurality of inlet openings throughout its length and around its entire periphery, is in effect a multiple offtake and no limitation to the specific structure illustrated is implied. The important thing is that the offtake for non-condensable gases be properly proportioned 100 to the cooling surface and to the amount of non-condensable gas present in the condensed steam. It is desirable that it be so positioned relatively to the cooling surface that the off flow of the non-condensable gases 105 assists the entering flow of steam to the cooling surface.

What is claimed is:-

1. In a condenser, the combination of a shell having an exhaust steam inlet; water tubes mounted in said shell and arranged in two main groups spaced apart to provide a substantially vertical steam lane to which said steam inlet leads; condensate deflecting plates extending substantially from the walls of said shell to the margin of said steam lane and serving to divide each main group of water tubes into a plurality of subgroups; conduits for the withdrawal of non-condensable gases mounted among the 120 water tubes of the various subgroups; and vacuum pump connections for said conduits. 125

2. In a condenser, the combination of a shell having an exhaust steam inlet; water tubes mounted in said shell and arranged in 130

two main groups spaced apart to provide a substantially vertical steam lane to which said steam inlet leads; condensate deflecting plates extending substantially from the 5 walls of said shell to the margin of said steam lane and serving to divide each main group of water tubes into a plurality of subgroups; conduits for the withdrawal of non-condensable gases, there being a conduit 10 for each subgroup positioned among the water tubes adjacent the walls of said shell; and vacuum pump connections for said conduits.

3. The combination with a water tube 15 condenser having its water tubes arranged within a shell in two main groups with an intervening steam and condensate lane leading from an exhaust steam inlet, at the top to a hot well below, of a plurality of reflectors extending from the shell to the sides of 20 said steam lane and arranged to subdivide said main groups into subgroups and to deflect the condensate from each subgroup into

said lane; and offtakes for non-condensable gases positioned among the tubes of the 25 various subgroups.

4. The combination with a water tube condenser having its water tubes arranged within a shell in two main groups with an intervening steam and condensate lane leading 30 from an exhaust steam inlet, at the top to a hot well below, of a plurality of deflectors extending from the shell to the sides of said steam lane and arranged to subdivide said main groups into subgroups and 35 to deflect the condensate from each subgroup into said lane; and an offtake connection for non-condensable gases extending longitudinally of each subgroup near said shell and having inlet openings for such gases at 40 points substantially throughout the length of the water tubes.

In testimony whereof I have signed my name to this specification.

WILLIAM LONSDALE.
